(57) **CLAIM**

The ornamental design for a “foldable table for aircraft interiors,” as shown and described.

DESCRIPTION

FIG. 1 is a top front perspective view of a foldable table for aircraft interiors which embodies my new and original design therefore;

FIG. 2 front elevational view thereof;

FIG. 3 is a rear elevational view thereof;

FIG. 4 is a top plan view thereof;

FIG. 5 is a bottom plan view thereof; and,

FIG. 6 is a right side elevational view thereof, the left side elevational view being a mirror image thereof.
